UNITED STATES PATENT OFFICE.

RICHARD O. RICHARDS, OF HURON, SOUTH DAKOTA.

DESIGN FOR A CAMPAIGN PIN OR BUTTON.

51,511.

Specification for Design.

Patented Nov. 20, 1917.

Application filed July 14, 1917. Serial No. 180,665. Term of patent 7 years.

To all whom it may concern:

Be it known that I, RICHARD O. RICHARDS, a citizen of the United States, residing at Huron, in the county of Beadle, in the State of South Dakota, have invented a new, original, and ornamental Design for a Campaign Pin or Button, of which the following is a specification, reference being had to the accompanying drawing, forming part thereof.

The figure is a plan view (on an enlarged scale) of a campaign pin or button illustrating my new design.

I claim—

The ornamental design for a campaign pin or button as shown.

R. O. RICHARDS.

Witnesses:

W. S. DAVIS,
MARTHA P. HALK.
